RADIO RECEIVER

Frederick W. Frink, East Orange, N. J., assignor to
 Federal Telephone and Radio Corporation, New
 York, N. Y., a corporation of Delaware

Application July 22, 1944, Serial No. 546,119

10 Claims. (Cl. 250—20)

1

This invention relates to radio receivers and more particularly to receivers tunable over a very wide range of frequencies.

In the past, radio receivers tunable over relatively broad bands of frequency have been proposed. However, in general, these receivers are limited to a given band width by the tuning characteristics of the input amplifier and the antenna systems. If broader band operation is required, it has generally been found necessary to provide additional receivers for these different bands which may be alternatively switched to a common reproducing unit.

It is an object of my invention to provide a relatively simple receiver circuit tunable over a very wide frequency band which may be considered as tunable over two contiguous frequency bands.

It is a further object of my invention to provide a super-heterodyne receiver circuit, wherein a single local oscillator serves to reduce the frequencies of one given receiving band to a common intermediate frequency and to reduce the frequencies of another band to the same frequencies as those of the first given band and subsequently to the same intermediate frequency.

According to a feature of my invention the beating oscillator which serves to reduce frequencies covering a normal given band from a first receiver unit to a common intermediate frequency is also used in a second mixer to reduce a second band of frequencies to the same frequencies as that of the first band named and thereafter to beat with these reduced signals to produce said common intermediate frequency. The first receiver unit and the second mixer unit are made alternatively operative so that in effect the receiver may be continuously tuned over a band representing both of these given ranges.

A better understanding of my invention and the objects and features thereof may be had from the particular description of a preferred embodiment thereof made with reference to the accompanying drawing, the single figure of which shows partly in schematic and partly in block circuit diagram a radio receiver unit incorporating the features of my invention.

At 1 is shown an antenna system operative over a lower frequency band coupled by means of a coupler unit 2 to the input circuit of a radio frequency amplifier 3. Radio frequency amplifier 3 is coupled to a mixer circuit 4 wherein the incoming signals are mixed with the energy from 50

beat oscillator 5 to reduce these incoming signals to a common intermediate frequency. The intermediate frequency signals in the output of mixer 4 are then applied to an intermediate frequency amplifier 6 from whence they may be coupled over a line 7 to a reproducing unit 8. Alternatively the signals from the intermediate frequency amplifier 6 may be applied over line 7 and a switch 9 to an indicator 10 if it is desired to determine the frequency of the received signals rather than to reproduce the signal energy.

A second antenna unit 11 operating over a higher frequency band is coupled over coupler unit 12 to a second mixer 13. Energy from beat frequency oscillator 5 is also applied to mixer 13 to reduce the signals incoming over antenna 11 and coupler 12 to the same range of frequencies as those received in amplifier 3. Second mixer 13 is coupled to the input circuit of mixer 15 so that these reduced signals may be further reduced to the common intermediate frequency after which they are amplified in intermediate frequency amplifier 6 and reproduced in reproducing unit 8 or indicated on indicator 10.

25 A switching circuit 14 is provided to control a switching unit 15 which may be in the form of a trigger circuit, for selectively rendering amplifier 3 and mixer circuit 13 operative. A tuning control means 16 serves to simultaneously tune the inputs of amplifier 3, mixer 4, beating oscillator 5 and second mixer 13 and to control electronic switching circuit 14. Tuning control means 16 may be manual control means or may be a motor driven means to continuously scan the receiver over the frequency bands. Furthermore, if desired, tuning control means 16 may be made selectively to operate either manually or under continuous motor control as desired, by arrangements well known in the art. Simultaneously with operation of electronic switch 14 an indicator control circuit 14a is preferably provided to control indicator 10 for the purpose of changing the indication depending upon whether the frequency band incoming over antenna 1 or 11 is effective at the time.

Turning more particularly to the circuit arrangements of the system, amplifier 3 may comprise a vacuum tube amplifier 17 to the input grid of which is applied signals, over tuned circuit 18 consisting of transformer secondary 19 and tuning condenser 20. The output energy from tube 17 is supplied to mixer circuit 4, by way of tuned input circuit 21, provided with a tuning condenser 22 cooperating with trans-

former primary 23. Condensers 20 and 22 are preferably simultaneously controlled so that circuits 18 and 21 are both progressively tuned to the frequencies of the incoming carrier energy received on antenna system 1. Energy from circuit 21 is then applied to the input grid circuit of mixer tube 24.

Beating oscillator 5 may comprise tube 25 operating as an oscillator at different selected frequencies by reason of the tuning of its tank circuit 26 consisting primarily of variable condenser 27 and the output primary coil 28. Primary coil 28 is coupled over secondary coil 29 and line 30 to the cathode lead of mixer tube 24 so that the output energy from oscillator 5 is applied to mixer circuit 4. As in known forms of super-heterodyne receivers, this beating frequency mixed with the incoming signals reduces the energy to a common, relatively fixed, intermediate frequency. In the output of tube 24 is provided tuned circuit 31 tuned to the fixed intermediate frequency. It will thus be seen that the signals incoming over antenna 1 are reduced to a common intermediate frequency. Condenser 27 of oscillator 5 is simultaneously adjusted together with condenser 22 so that the frequencies of oscillator 5 and tuned circuit 21 are properly tracked to produce the single intermediate frequency.

The signals incoming over antenna 11 are of such a frequency that they differ from those incoming over antenna 1 by amounts equal to the frequency of beat frequency oscillator 5. These incoming signals are applied over a tuned circuit 32 consisting primarily of transformer secondary 33 and tunable condenser 34 to the input of second mixer tube 35. At the same time energy from beat oscillator 5 is applied over transformer secondary 36 and line 37 to the cathode of the second mixer tube 35 so that the incoming energy over antenna 11 and the energy from beat frequency oscillator 5 will be mixed in tube 35. Condenser 34 is suitably coupled for simultaneous tuning with condenser 27 so that the reduced frequency, output energy from tube 35 will cover the same frequency range as the input energy incoming over antenna 1. These reduced frequency signals from mixer tube 35 are then applied over line 38 to tuned input circuit 21 of mixer 4, for mixing in tube 24 with the beat frequency oscillations from oscillator 5 applied thereto over transformer secondary 29 and lead 30. It will thus be seen that the frequencies of this second band are reduced to the same ultimate intermediate frequency as those of the first band for reception and reproduction.

If amplifier 3 and second mixer 13 are simultaneously effective, it is clear that two separate frequencies may simultaneously be received and reduced to a common intermediate frequency. This might result in confusion and interference in the receiver or indicator. To prevent such an operation I provide a switching arrangement which may be a known electronic switching circuit, as indicated at 14. This switching circuit may be coupled over line 39 to the grid of tube 40 of flip-flop or triggered switching control circuit 15. This circuit including tubes 40 and 41, is normally biased so that tube 40 is inoperative while tube 41 is conductive. When control energy from 14 is applied to tube 41, this tube becomes conductive and tube 40 non-conductive during the time this switching energy is applied. Switching circuit 14 may be adjusted so that tubes 40 and 41 are alternately conductive for the same

period of movement of tuning control means 16. This period is preferably such that condensers 20 and 22 are swept through one complete control cycle of the incoming frequency band of antenna 1. During the period when tube 41 is conductive, blocking energy is applied over potentiometer resistor 42 and control line 43 to the control grid of tube 35 in second mixer 13. Thus during this period the receiver is responsive to energy incoming over antenna 1 and coupler 2 but is blocked for energy incoming over antenna 11 and coupler 12. When the electronic switching circuit, however, applies potential to the grid of tube 41 so that this tube becomes conductive, then a blocking potential is applied over potentiometer 44 and conductor 45 to the grid of tube 17 of amplifier 3 blocking this circuit and permitting energy incoming over antenna 11 and coupler 12 to be passed through the receiver circuit to the reproducing or indicator units.

When the circuit is used merely for selectively receiving one station over the entire double frequency sweep, no special control is necessary at reproducing unit 8. However, when it is desired to use the system for searching out transmitters and determining their frequencies, switch 9 may be closed so that indicator 10 is in circuit. Indicator 10 may be of any desired form such as a pair of separate frequency indicating meters or any other form of frequency indicating device. The position in the frequency spectrum of the received signals may be made for example, along a sweep line timed for operation with rotation of the tuning condensers. However, since the energies incoming over antennas 1 and 11 are reduced to the same frequency value, and the tuning condensers sweep through their tuning cycles twice to cover the entire double band it is preferable to switch indicator 10 simultaneously with the effective switching of energy from antennas 1 and 11 so that the indications will appear on definite separate scales. For this purpose, any form of control switching unit, such as shown at 14a may be operated under control of switching circuit 14 simultaneously with the operation of the flip-flop circuit 15 so that the proper scale will be indicated. Since the particular form of indicator used is not material to the operation of the system of this invention, details of the circuit are omitted.

It will be clear that in accordance with my system, a frequency band equivalent to two separate normally received bands may be effectively received on a continuously tuned receiver circuit. Other forms of circuit arrangements incorporating the broad features of my invention will readily occur to those skilled in the art.

While I have described a specific application of my invention to a receiver unit, it should be distinctly understood that this is made merely by way of illustration and is not intended as any limitation on my invention as set forth in the objects thereof and in the accompanying claims.

I claim:

1. In a radio receiver tunable over different related first and second frequency bands, a common mixer circuit, a first source of energy within said first frequency band, a second source of energy within said second band, an oscillator tunable over a band of frequencies differing by a given frequency from the frequencies of said first band and differing by the frequencies of said first band from the frequencies of said second band, mixer means for mixing energy from said second source and energy from said oscillator

fator to provide frequencies respectively equal to the frequencies of said first band, means for applying energy from said oscillator to said common mixer circuit and means for selectively applying energy from said first source band and energy from said mixer means to said common mixer circuit to provide output energy from said common mixer circuit at said given frequency over the entire range of said first and second bands.

2. The method of reducing energy received in different related first and second frequency bands to a common frequency by means of a single oscillator, comprising tuning said oscillator over a frequency band equal to the difference frequency of said first and second bands and differing from the frequencies of said first band by said common frequency, mixing the energy output of said oscillator with the energies of said second band to reduce them to the same frequencies as said first band, and selectively mixing the energy output of said oscillator with the energies of said first band and with the reduced frequency energies of said second band, to provide said common output frequency over said bands.

3. A radio receiver tunable for operation over a wide frequency band, comprising first means for receiving signals over one portion of said band, second means for receiving signals over the other portion of said band, an oscillator tunable over a given range of frequencies differing by a given intermediate frequency from the frequencies in said one portion of said band, and differing from the frequencies of said other portion of said band by amounts equal to the frequencies of said one portion of said band, means for mixing the energies from said oscillator and said other portion of said band to provide frequencies equivalent to the frequencies of said one portion of said band, a mixer circuit, means for supplying energy from said oscillator to said mixer circuit, and selective means for selectively applying energy from said first means and energy from said mixing means to said mixer circuit to produce output energy from said mixing circuit at said given intermediate frequency over said entire frequency band.

4. A receiver according to claim 3, further comprising means for continuously varying the tuning of said mixing means and said oscillator over their given ranges, and means for alternately rendering said first means and said mixing means effective.

5. A receiver according to claim 3 wherein said selective means comprises a trigger circuit for rendering the system operative to alternately pass signals from said first and second means, and electronic control means for controlling operation of said trigger circuit.

6. A receiver according to claim 3 further comprising a reproducing means for reproducing indications characteristic of the signals received over said band.

7. A receiver according to claim 3 further comprising indicator means responsive to signals from said first and second receiver means coupled to the output of said mixer circuit, and means controlled synchronously with said selective means for controlling said indicator means.

8. A radio receiver operative over a wide frequency band, comprising a first receiver means tunable over a first frequency range, a first mixer circuit, a tunable heterodyne oscillator, means for applying signals from said first receiver means and the energy from said oscillator to said mixer circuit to produce a given intermediate frequency, a second receiver means responsive to frequencies in a second range contiguous to said first range, a second mixer circuit, means for applying signals from said second receiver means and energy from said oscillator to said second mixer circuit to produce other intermediate frequencies corresponding in range to the frequencies of said first band, and means for applying energy from said second mixer circuit to said first mixer circuit simultaneously with energy from said oscillator to produce output energy of said given intermediate frequency, whereby signal energy over a band equal to said first and second ranges may be received.

9. In a radio receiver comprising an amplifier tunable over a first frequency range, a first mixer circuit having an input tunable over said first frequency range coupled to said amplifier, an oscillator tunable over a given frequency range to produce a constant difference frequency between the oscillator energy and the energy of said first frequency range, and means for applying energy from said oscillator to said mixer circuit to produce an intermediate frequency at said constant difference frequency, an arrangement for effectively extending the range of said receiver comprising a second mixer circuit having an input tunable over a second range of frequencies differing from the frequencies of said oscillator by the frequencies of said first range, means for applying energy from said oscillator to said second mixer circuit to produce intermediate frequencies within said first frequency range, means for applying said produced intermediate frequencies to the input circuit of said first mixer circuit, means for simultaneously tuning said mixers and said oscillator over their respective ranges, and means for rendering said amplifier and said second mixer alternately effective.

10. In a super-heterodyne receiver having an amplifier, a local oscillator, and a receiver mixer coupled to said amplifier and said local oscillator for reducing a given band of received frequencies to a given intermediate frequency, a further system for effectively extending the range of said receiver to an adjacent band of other frequencies comprising a reducing mixer circuit tunable over a second range of frequencies differing from the frequencies of said local oscillator by the frequencies of said given band, means coupling said oscillator to said reducing mixer to reduce the frequencies of said second range to the same values as those of said given range of frequencies, means coupling the output of said reducing mixer to the input of said receiver mixer, and means for selectively effectively applying the outputs of said amplifier and said reducing mixer to said receiver mixer, whereby the frequencies of said second range of frequencies are also reduced to said common intermediate frequency.

FREDERICK W. FRINK.
